US00D651129S

(12) **United States Design Patent**
Wang

(10) **Patent No.:** **US D651,129 S**
(45) **Date of Patent:** **** Dec. 27, 2011**

(54) **DOUBLE LAYER COIL ZIPPER SLIDER
WITH NOSE**

D556,087 S * 11/2007 Lin D11/221
D612,293 S * 3/2010 Cossutti D11/221
D627,683 S * 11/2010 Ynna D11/211

(76) Inventor: **Lien-Chou Wang**, Taipei (TW)

* cited by examiner

(**) Term: **14 Years**

(21) Appl. No.: **29/396,458**

(22) Filed: **Jun. 30, 2011**

(51) **LOC (9) Cl. 02-07**

(52) **U.S. Cl. D11/221**

(58) **Field of Classification Search** D11/200,
D11/201, 221; 24/381-383, 385-387, 414-417,
24/421-422, 427-431, 433; 2/265

See application file for complete search history.
